ELECTRIC INCANDESCENT LAMP

Carl Trope, Berlin-Steglitz, Germany, assignor
to General Electric Company, a corporation of
New York

Application March 12, 1935, Serial No. 10,723
In Germany April 10, 1934

2 Claims. (Cl. 176—27)

My invention relates to electric incandescent lamps and particularly to multiple filament lamps. Still more particularly my invention relates to incandescent lamps comprising two or more filaments, one of which is normally operative, and means for automatically bringing into the electrical circuit another filament when the normally operative filament burns out.

In lamps of the type referred to above it has heretofore been proposed to provide a spring switch which is held in the open position by the normally operative filament and released by the burning out of said filament, thereby closing the circuit through another filament. Such devices have not come into practical use because the tensile strength of the filament when heated to an incandescable temperature is too low to provide a positive means for holding the spring switch in the open position. In another proposed arrangement, the normally operative filament was divided into two branches connected in parallel and the mid points of said branches were connected by wires to the ends of a fuse wire which was bent around the end of a spring switch arm. When one of the branches of the normally operative filament burned out, the balance of current in the branches was upset so that some current passed through the fuse and ruptured it, thereby releasing the said switch arm and connecting a second filament in the circuit. This structure was objectionable because it was so complicated and the fuse, being stressed intensively at one point in a lateral direction by the spring switch arm, was liable to be broken prematurely, particularly if subjected to vibrations.

The present invention is based on the fact that when a filament burns out, the current rises as the windings of a coiled filament come in contact or as a small arc is formed between the broken parts of the filament. This is particularly so when the lamp has a gas filling rich in argon and the filament is of a concentrated form such as a coiled coil. This rise in current is sufficient to rupture a wire-shaped fuse connected in series with the filament. With this knowledge as a basis a considerably simplified construction of multiple filament lamp may be made by connecting a spring switch arm in series with a fuse wire which is also in series with the normally operative filament. When the filament burns out and the current rises, the fuse is ruptured and the switch arm is released, thereby connecting another filament in the circuit.

For a further understanding of the invention,

reference may be had to the drawing in which Fig. 1 is a diagrammatic view of the circuit arrangement of a lamp comprising my invention; and Fig. 2 is a similar view of a slightly modified circuit.

Referring to Fig. 1, the lamp comprises a normally operative filament 10 and an auxiliary filament 11 which are sealed in the usual glass bulb (not shown). The said filaments are connected at one side to a common lead wire 13 which is electrically connected to one of the lamp base terminals. The opposite ends of said filaments 10 and 11 are connected to lead wires 14 and 15 respectively, said lead wire 14 being electrically connected to the other lamp base terminal. A fuse wire 16 and a spring switch arm 17 are incorporated in the lead wire 14 in series with the filament 10. The switch arm 17 may be provided with a contact 18 and the lead wire 15 with a contact 19. Since the switch arm 17, or its contact 18, is held out of engagement with the lead wire 15, or its contact 19, by the fuse wire 16, only the filament 10 is normally operable. When the said filament 10 burns out, the fuse 16 is ruptured by the rising current flow, thereby releasing the spring switch arm 17 so that the contact 18 thereon engages the contact 19 and connects the auxiliary filament 11 into the circuit. The rupturing of the fuse 16 also prevents the blowing of the main fuse located in the supply line.

In Fig. 2 parts corresponding to similar parts in Fig. 1 have been correspondingly numbered. The lead wire 13 is connected directly to filament 10 as in Fig. 1, but a separate branch lead wire 20 is connected to said lead wire 13 and to the filament 11, and a fuse wire 21 is incorporated in said lead 20 to prevent blowing of the main line fuse when the auxiliary filament 11 burns out.

What I claim as new and desire to secure by Letters Patent of the United States is:

1. In an electric incandescent lamp, the combination of a normally operative filament and an auxiliary filament, one end of each of said filaments being electrically connected to one terminal of the lamp, a spring switch arm electrically connected at one end to the other terminal of the lamp, and a fuse wire in series with said normally operative filament connected to the other end of said switch arm and holding said switch arm out of circuit engagement with said auxiliary filament, said fuse wire being of sufficient size to carry the normal current through

said normally operative filament but not an abnormal current, said switch arm moving into circuit closing engagement with said auxiliary filament when released by the rupturing of said fuse 5 wire.

2. In an electric incandescent lamp, the combination of a normally operative filament and an auxiliary filament, one end of each of said filaments being connected to one terminal of the 10 lamp, a lead wire connected to the other end of said auxiliary filament, a spring switch arm electrically connected at one end to the other terminal of the lamp and disposed adjacent said lead

wire, and a fuse wire in series with said normally operative filament connected to the other end of said switch arm and holding said switch arm out of engagement with said lead wire of said auxiliary filament, said fuse wire being of sufficient size to carry the normal current through said normally operative filament but not an abnormal current, said switch arm moving into engagement with the said lead wire of said auxiliary filament to close the circuit therethrough when released by the rupturing of said fuse wire. 10

CARL TROPE.
